(57) **CLAIM**

The ornamental design for a charging station for robot as shown and described.

DESCRIPTION

1. Charging station for robot

1.1: Front

1.2: Back

1.3: Left

1.4: Right

1.5: Top

1.6: Bottom

1.7: First perspective view

1.8: Second perspective view

1.9: Front view in unfolded state

1.10: Back view in unfolded state

1.11: Left view in unfolded state

1.12: Right view in unfolded state

1.13: Top view in unfolded state

1.14: Bottom view in unfolded state

1.15: First perspective view in unfolded state

1.16: Second perspective view in unfolded state
